(57) **CLAIM**

The ornamental design for a filter device for rainwater downpipes, as shown and described.

DESCRIPTION

FIG. 1 is an exploded perspective view of a filter device for raindrop downpipes showing our new design. The broken line showing is for illustrative purposes only and forming no part of the design;

FIG. 2 is a front view of the filter device as shown in FIG. 1, with the components assembled together;

FIG. 3 is a perspective view of the upper section of the filter device body;

FIG. 4 is a perspective view of the middle section of the filter device body; and,

FIG. 5 is a perspective view of the lower section of the filter device body.
